ALBERT HOWARTH, OF PROVIDENCE, RHODE ISLAND, ASSIGNOR, BY MESNE ASSIGNMENTS, TO STAR CARBURETOR AND SUPPLY COMPANY, OF PROVIDENCE, RHODE ISLAND, A CORPORATION OF RHODE ISLAND.

CARBURETER.

1,032,547.

Specification of Letters Patent. Patented July 16, 1912.

Application filed July 24, 1909. Serial No. 509,380.

To all whom it may concern:

Be it known that I, ALBERT HOWARTH, a citizen of the United States, residing at Providence, in the county of Providence and 5 State of Rhode Island, have invented certain new and useful Improvements in Carbureters, of which the following is a specification, reference being had therein to the accompanying drawings.

10 Like reference characters represent like parts.

Figure 1 is a front elevation of my improved carbureter. Fig. 2 is a side elevation of the same, the throttle valve and air valve 15 being partially open. Fig. 3 is a bottom plan view as seen on line *a a* of Fig. 1. Fig. 4 is a cross sectional view as seen on line *c c* of Fig. 5. Fig. 5 is a central vertical section as seen on line *b b* of Fig. 1. Fig. 6 20 is a view partly in elevation and partly in section as seen on line *e e* of Fig. 1. Fig. 7 is a view partly in plan and partly in section as seen on line *d d* of Fig. 5. Fig. 8 is an isometric view of the combined throttle valve and air valve, together with the gasoline-feed needle mounted therein. Fig. 9 is a cross sectional view of the gasoline-feed needle (on an enlarged scale) as seen on line *f f* of Fig. 8. Fig. 10 is a view of 25 the mixing chamber and the bottom thereof, as seen in section on line *g g*, of Fig. 3, and includes a sectional view (on said line) of the conical nozzle and of its tube.

My invention relates to the class of carbureters for gas-explosive engines adapted to 35 use for propelling automobile vehicles and for other work; and it consists of the novel construction and combination of the several parts and elements hereinafter described as 40 set forth in the claims.

In the drawings, the reference numeral 1 indicates the mixing chamber of the carbureter, having at its upper end an annular constriction or neck 2, and an axially directed, concentric, tubular extension 3, whose inner surface is threaded, as seen in Fig. 5. The outer peripheral surface of the tubular extension 3 has the hexagonally-arranged wrench-faces 4, illustrated in Figs. 1 45 and 2. An outlet pipe 5 is in threaded connection with the tubular extension 3 and serves to conduct to the engine (not shown) the carbureted air produced by the carbureter. The mixing chamber 1 also has at its

bottom the tubular extension 6, which has the 55 interior screw thread, shown in Fig. 5. It also is provided with the two ear-pieces 7, 8, through which a binding screw 9 passes, as seen in Figs. 1, 2 and 5.

The mixing chamber 1, has on one side a 60 tubular extension 10 to contain a relief air valve as hereinafter described. A shaft 11 passes through apertures made therefor in the mixing chamber 1 and also through the bosses 12, 13, integral with said mixing 65 chamber and forming therewith the bearings, in which the shaft 11 is so mounted as to be capable of an oscillatory movement therein. The shaft 11 is oscillated by power, applied by the operator to a lever (not 70 shown), whose end is connected by a link or rod 14 to the end of a crank or arm 15 by means of a pivotal screw as illustrated at 16. This crank or arm 15 is mounted upon one end of the shaft 11, as best seen in Fig. 2, 75 and fastened thereto by a key or spline 17. For this purpose the crank arm 15 is made with a tubular hub or head 18. A sector-shaped piece 19, integral with the crank arm 15 (at the end which is adjacent to the 80 tubular hub or head 18) has the two flanges or bosses 20 and 21. A regulating or adjusting screw 22 is mounted in and through the boss or flange 20, as shown in Fig. 2, and is held in its adjusted position by a check 85 nut 23. The crank arm 15 carries a valve 24, preferably integral therewith and of the substantially hook-shape illustrated in Fig. 2.

From one side of the mixing chamber 1, a 90 stop pin 25 projects, with which the boss or flange 21, of the sector-piece 19 of the crank arm 15 and also the inner end of the adjusting screw 22 are alternately brought in contact, thus limiting the extent of the oscillation of the crank arm 15 and the shaft 11, on which the crank arm is fastened. The shaft 11 carries the curved arm or cam 26, which has the curved cam edge 27 and which is mounted on the shaft by its tubular head 100 28, and fastened thereon by the pin 29.

The mixing chamber 1 has a sector-shaped aperture 30, shown by dotted lines in Fig. 5 and partially by full lines in Fig. 6. The mixing chamber 1 is made with an exterior 10 flat bottomed recess, represented in Fig. 6, around which is an arc-shaped rim 31, with a flat face. A sector-shaped, diaphragm valve-

2
stop 32 is secured by a screw 33 to the mixing chamber 1 in the bottom of the recess. An auxiliary air valve 34 has an arc-shaped periphery, about 234° in extent, and is movable in said recess in sliding contact with the bottom thereof, being concentric with said recess. The outer plane surface of the air valve 34 is flush with the adjacent plane surface of the carburetor body 1, as seen in Figs. 4 and 6. A portion of its periphery is toothed or serrated, as illustrated in Fig. 6 at 35. A handle 36 preferably integral with the valve 34 extends radially therefrom. The acute-angled point of the valve stop 32 furnishes a bearing, against and upon which the obtuse-angled portion of the radial surfaces of the air valve 34 is in contact, and so allows said valve to oscillate concentrically in said recess to cover or uncover, at the will of the operator, the aperture 30 of the mixing chamber 1. The air valve 34 is supported in position by the inner plane face of the hook-shaped valve 24, which is slidable on the flat face of the rim 31 and on the exposed plane surface of said air valve 34, and it is also supported by the inner plane surface of the flange 20 of the crank arm 15, which flange is slidable on the outer plane surface of the air valve 34, as represented in Fig. 1, but most clearly in Fig. 4.

An integral tube 37 extends vertically along one side of the mixing chamber 1 at the bottom thereof, and in the bore of said tube is a spiral spring 38. A friction plug 39, having a sharpened or pointed upper end, is mounted in said bore and the inner end of the spring 38 bears against the adjacent squared end of said plug. An adjusting screw 40 is in threaded engagement with said bore and furnishes a bearing for the outer end of the spring 38, and thus regulates the tension of said spring. The protruding sharpened end of the plug 39 is 45 conical and engageable with the teeth or serrations 35 of the auxiliary air valve 34, thus securing the said valve in its adjusted position. The contact of the valve handle 36 with the tube 37 limits the movement of the valve 34 in one direction and the contact of said valve handle with the end 41a of the rim 31 of said recess limits the movement of the valve 34 in the opposite direction.

A diametrical piece or web 41 extends 55 across the tubular extension 10 and is provided with a central bearing 42. A disk 43 constitutes a relief valve and has a central threaded aperture. The relief valve stem 44 has an outer head 45, which is in snug 60 contact with the central boss of the disk 43, as seen in Figs. 4 and 5, being engaged with said disk by screw-threads, as shown. The cylindrical portion of the valve stem 44 slides loosely in the bearing in the web 41.

65 The valve stem has a head 46 at its inner

end. A spiral spring 47 surrounds the valve stem 44 and has its bearing at one end against the head 46, and also has its opposite bearing against the rear surface of the bearing 42. By force of this spring the disk 43 is normally held in close contact with the outer circular edge of the tubular extension 10.

The chamber 48 has an upwardly-directed, tubular extension 49, provided with an external screw-thread, by which it engages the threaded bore of the tubular extension 6 of the mixing chamber 1, as seen in Fig. 5. This chamber 48 has in its upper half a cylindrical bore, but in the lower half this bore spreads conically. A water jacket 50 surrounds the chamber 48, as represented in Fig. 5. The water jacket 50 is tapped in two places, diametrically opposite each other, for the reception of two pipes 51 and 52, to supply water thereto. Two air-valve apertures 53, 54, open through the chamber 48, being diametrically opposite to each other as shown in Figs. 1 and 2 in solid lines, and one of them is shown in Fig. 5 in dotted lines. The sides and bottom of each air inlet or aperture 53 are tapered, as shown in solid lines in Figs. 2, 7 and 10 and in dotted lines in Fig. 5.

The chamber 48 has a bottom 55, shown in Figs. 3 and 10, and is provided with an annular flange 56, a portion of which is toothed or serrated, as illustrated in said Fig. 3 and in Figs. 1, 2 and 5 at 57. Through the bottom 55 of the chamber are the two diametrically opposite air-inlet holes 58, 59, for the entrance of primary air. The water jacket 50 is provided with a plug 60, by the removal of which the contents of the water jacket may be drained. A nozzle or cone 61 for supplying gasoline to the chamber 48 has a tubular stem 62, the upper end of whose bore is threaded as shown at 63, and is also provided with a concentric enlargement, as seen at 64. The lower part of the stem 62 has the external thread 65 and just below the conical head 61 is threaded externally, as seen at 66. The diameter of the threaded tube 62 at 65 is somewhat less than the diameter of said threaded tube 115 at 66.

The primary air valve is designated as 67. It has a central enlargement 68, provided with a circular aperture, by means of which it is loosely mounted on the tube 62, as best 120 illustrated in Fig. 5, in contact with the lower annular edge of the cone head 61. The valve 67 has a handle 69, extending therefrom with a bend 70. The valve 67 has a projection 71 formed therein, which engages with the teeth or serrations 57 of the flange 56 of the chamber 48, to lock said valve in position. The nut 72, engaging the threads 66 of the tube 62, supports the primary air valve 67 in place, as shown in Fig. 130

5. The hole in the nut 72 is large enough to allow said nut to slip loosely over the screw threads 65 in moving up along the lower end of the tube 62 to its engaging position illustrated in Fig. 10. The primary air valve 67 has a limited rotation on the tube 62, so as to cover or uncover the air inlet holes 58, 59, as the operator desires. This action of the primary air valve is best illustrated in Fig. 3.

10 A gasolene-feed regulator 73 has a plurality of radially directed holes, one of which is shown at 74. From the inner ends of these holes an axially-directed passage 15 extends upwardly, as represented in dotted lines in Fig. 5. The holes 74 open into the chamber or enlargement 64 of the tube 62. The tube 62 has the pipe 75, whose inner end opens into the chamber or enlargement 20 64 of the tube 62. A gasolene supply pipe 76 is in threaded connection with the outer end of the pipe 75 and conducts gasolene from a tank or other source (not shown). The gasolene-feed regulator has at its upper 25 end a screw-threaded connection with the threaded portion 63 of the bore of the cone head or nozzle 61. A handle 78, passing through the lower portion of the gasolene-feed regulator, enables the latter to 30 turn upon the screw-threads 63. A washer 79 lies just beneath the concaved annular edge 77 of the tube 62 and is held in position by the nut 80, which engages the screw-threads 65, as represented in Fig. 5.

35 A gasolene needle-valve seat 81 fits in the upper end of the bore of the conical head or nozzle 61, as seen in Fig. 5, and has an axial longitudinal passage through it. The gasolene needle valve comprises three 40 parts,—a head 82, which has a rounded bottom and conically tapering sides and fits the concavity of the valve seat 81, as shown in Fig. 5; a cylindrical stem 83, extending up axially from the upper larger end of the 45 valve head 82; and a long needle 84, which extends axially downward from the smaller end of the valve head 82. The needle 84 extends loosely in the longitudinal, axial bore of the gasolene feed device shown in Fig. 5.

50 The valve stem 83 is provided with a transverse hole, in which is inserted a cross pin 85. The needle 84 is shown in cross section on an enlarged scale, the straight surface indicated by 86 in Fig. 9, extends diagonally with respect to the axial line of said needle, as represented in Fig. 8, so that the needle tapers on said surface, and the needle is larger at the top of said taper than at the end of the taper. The needle 84 may, however, be simply tapered concentrically to form a long cone, if preferred.

55 A piston valve 87 fits in the bore of the chamber 48 and is slidable therein. It is a combined throttle valve and air valve. It 60 has near its upper end the outlet openings

88 for the discharge of carbureted air, which openings extend between the posts 89. There is a diametrically-extending web piece 90, in which is a tubular bearing 91. The stem 83 of the gasolene needle valve is 70 loosely mounted in the bearing 91. The cylindrical portion 92 of the piston, when the parts are in the position represented in Fig. 5, shuts down over and closes the apertures 53 and 54, as seen in Fig. 5. The piston valve has a solid top 93, which is integral with the tubular portion of the piston. When the piston is in the position shown in Fig. 5, the top 93 is almost flush with the top edge of the tubular extension 6 of the chamber 48, but it is a very little above said edge. When the parts are in the position shown in Fig. 5, the air outlet openings 88 are closed by the inner surface of the tubular extension 6, and the air inlet openings 53 are closed by 85 the cylindrical sides of the piston valve. By means of the cross pin 85, the valve stem 83 of the gasolene needle valve is supported loosely within the piston valve, as shown in Fig. 5.

90 A priming stud 94 has a threaded stem 95 (shown in dotted lines in Fig. 5), which extends through and is fastened in the bottom 55 of the chamber 48, and is provided with hexagonally-disposed faces and also with a downward cylindrical extension 96. A priming swivel 97 has at one end an aperture to receive loosely the end of said extension, which, when the parts are assembled, is headed over to sustain said swivel in position. The outer portion of the swivel 97 is bifurcated and is bent at a right angle to extend vertically downward. A priming lever 98 is mounted between the bifurcated ends of the swivel and is pivoted thereto at 95 100 105 110 115 120 125 130 99. An operating wire 100 is secured to an eye in the upper end of the lever 98, as seen at 101. The priming stud 94 and its extensions are tubular, and a priming pin 102 is mounted slidably in the tube. The priming pin 102 has a head 103, and a spiral spring 104 surrounding said pin has its upper end bearing against the headed-over end of the extension of the stud 94 and its lower end bearing against the head 103, of the pin 102. The lower, bent, free end of the priming lever 98 extends beneath the head 103 of the pin 102 in contact therewith and supports said pin in position. The upper end of the priming pin 102 is in contact with the lower edge of the piston valve at one point thereof, as illustrated in Fig. 5.

As shown in Fig. 5, the operative end of the curved arm or cam 26 is in contact with the top 93 of the piston valve, when the parts are in the position there illustrated. The piston 87, 92, is a free piston, that is, it is not operated by a piston rod, but is movable in one direction by the suction of the engine, and in the opposite direction by 130

gravity or the back pressure of the explosion.

Having thus described the several parts of my improved carbureter, I will now explain the mode of its operation. This carbureter belongs to the class of suction-operated carbureters, and includes some of the characteristic features of my improved carbureter shown and described in Letters Patent of the United States, No. 958,128, granted to me May 17, 1910, for improvement in carbureters. In carbureters of this class the throttle valve is opened entirely (or principally) by the suction of the engine, instead of by the use of mechanically movable devices. Suppose that the carbureter is in its non-operative position and at rest, as shown in Fig. 5. At this time the curved arm or cam 26, fastened on the shaft 11, is directed downwardly and presses down the top 93 of the piston valve, so that said top is flush (or approximately flush) with the upper annular edge of the tubular top or extension 6 of the chamber 48. The auxiliary air valve 24 partially closes the air inlet 30, as shown in Fig. 2. The primary air valve 67 partially closes the air-inlet openings 58, 59, as illustrated in Fig. 3. The air-outlets 88, 88, of the piston valve are closed by the tubular extension 6 of the chamber 48, as shown in Fig. 5. The air inlet openings 53 and 54 are closed by the cylindrical side of the piston valve, as seen in Fig. 5. The flow of gasoline is stopped by the seating of the cone head 82 in the valve seat 81, and by the seating of the needle 84 in the passage of the gasoline-feed regulator, as shown in Fig. 5.

The carbureter is set in operation as follows. The chauffeur draws the link bar 14 in the direction indicated by the arrow 105 in Fig. 5, thereby rocking the shaft 11, which lifts the end of the curved arm or cam 26 from its forcible contact with the top 93 of the piston valve, so that the piston valve is thereafter ready to rise whenever motive power is applied for that purpose. The rise of the piston valve is limited by the cam 26, when said cam has been elevated by the oscillation of the shaft 11. The chauffeur then cranks the engine as usual, and gives the initial charge of gasoline to the carbureter by drawing the wire 100 in the direction indicated by the arrow 106, thereby raising the free, lower end of the priming lever 98. This movement of the lever 98 lifts the priming pin 102, and compresses the spring 104 (which spring, when released by the cessation of the power drawing the wire, returns said parts to their former, normal position). The rise of the priming pin 102 lifts the piston valve. When the piston valve so rises, three results are accomplished: the gasoline needle valve is slightly raised; the air inlets 53 and 54 are slightly

uncovered, and the air outlet openings 88 are also slightly uncovered, as they come up above the top annular edge of the tubular extension 6 of the chamber 48. As the level of the gasoline in the supply tank (not shown) is above the level of the valve seat 81, the gasoline is discharged from the valve seat 81 by gravity, and is mingled with the air, which comes through the air inlets 53 and 54; and the explosive mixture, so formed, passes out through the apertures 88 of the piston valve and passes through the mixing chamber 1 and the pipe 5 to the engine, and is ignited or exploded in the usual manner. The operation of the carbureter, having been thus established, continues automatically until the chauffeur reverses the movement of the link 14, thus rocking the shaft 11 reversely, and so causes the curved arm or cam 26 to press down to its former position the piston valve. Consequently the air openings of said valve and of the chamber are closed again and the flow of gasoline is stopped.

The gasoline is supplied to the carbureter through the pipe 76 from a tank or other source, (not shown). It flows by gravity from the pipe 76, through the pipe 75, into the annular chamber or enlarged space 64 within the tube 62. Thence it flows through the inlet holes 74 and up through the vertical passage shown in dotted lines in Fig. 5, and as the needle valve 84, is lifted, the gasoline is discharged into the chamber 48 in the open bottom of the piston valve, as already explained. The amount of gasoline so discharged depends on the amount of clearance of the tapered surface 86 of the needle 84 within the bore or passage of the gasoline-feed regulator. The degree of such clearance is determined by means of the handle 78, by which said regulator is turned upon the screw threads 63 of the cone head or nozzle 61. The more the regulator is screwed up, the less the amount of the clearance and discharge; the lower it is unscrewed, the greater is the amount of the clearance and discharge. It is to be observed that the gasoline is broken up into spray and vapor by the impinging of two differently directed sets of air currents, the vertical air currents which pass up through the air inlets 58 and 59 at the bottom of the mixing chamber, and the horizontal air currents which pass radially inward through the air inlets 53. These vertical air currents and horizontal air currents strike one upon another adjacent to the valve seat 81 and valve head 82, and so dissipate the jet of gasoline there delivered, thus mixing thoroughly the gasoline vapor and air to produce the carbureted air. The washer 79, and packing nut 80, constitute a stuffing box to prevent the leakage of gasoline.

In order to diminish the richness of the mingled gasoline vapor and air, mixed within the piston valve and discharged therefrom into the mixing chamber 1, I use the auxiliary air valve. By the oscillation of the crank 15, as the link 14 is drawn in the direction indicated by the arrow 105 (Fig. 5), the aperture 30 in the body 1 of the carbureter is uncovered to some extent, by the sliding 10 of the valve 24 across it, as best illustrated in Fig. 2, whereupon the atmospheric air rushes in through the aperture 30 and reduces the richness of the mixture by adding thereto more air. The amount of such auxiliary air supply through the aperture 30 is 15 regulated by adjusting the position of the auxiliary air valve 34. By moving the handle 36, as much of the opening 30 can be uncovered as desired, and the valve 34 is held 20 in its adjusted position by the engagement of the plug 39 with that tooth 35 of the series of serrations, which then receives the pointed end of the plug, the spring 38 serving to maintain such engagement. It is observed 25 that this valve 34 has no central pivot, on which to oscillate, but its arc-shaped edge in sliding contact with the arc-shaped rim 31 of the recess, wherein said valve is mounted, coöperating with the 30 acute-angled point of the piece 30 and the obtuse-angled edge of the valve, constitute a substitute for a pivot and give the requisite fulcrum action. Thus the valve 34 may wholly close the opening 30, or may fully 35 uncover said opening, or may partially close or open it to any intermediate degree. The clamping action of the binding screw 9 draws the ear pieces 7 and 8 together and firmly secures the mixing chamber 1 of the 40 carbureter to the tubular top 6 of the chamber 48, as illustrated in Fig. 5. In case of any extreme gas pressure within the carbureter mixing chamber 1, the relief valve, shown in Figs. 4, 5 and 6 acts automatically. 45 The spring 47 is of any desired tension and normally closes the disk, or valve 43 into forcible closing contact with the outer annular edge of the tubular extension 10, as shown in Figs. 4 and 5. But if the gas 50 pressure within the mixing chamber exceeds the pressure of the spring 47, the disk or valve 43 is pressed outwardly, as represented in Fig. 6, whereupon the excess of gas pressure is relieved by the access of atmospheric air. The spring 47 then being 55 free to act, automatically closes the relief valve to the normal position shown in Figs. 4 and 5.

In the regular, usual operation of the carbureter, the upward movement of the piston valve is caused by the suction of the engine. The downward movement of the piston valve is caused by the action of gravity, or by back pressure. When, however, it is desired to stop the engine, the link 14 is re-

versed, thus rocking the shaft 11 reversely, and this oscillation of the shaft 11 brings down the curved arm or lever 26 forcibly, and so presses down the piston valve to the position shown in Fig. 5. Then the gasoline feed is stopped, the air inlets 53 are closed, the air outlets 88 are closed, and the air inlet 30 is closed as far as the adjustment of the valve 34 will permit. However, for priming purposes, whenever the curved arm or cam 26 has been raised, as already explained, the piston valve is capable of a rising movement by operating the wire 101 and the lever 98, as has been described. The closure of the piston valve automatically by gravity is a more reliable and quicker action than a closure of it by mechanically operated means. When the piston valve descends to the position represented in Fig. 5, the valve head 82 instantly shuts into its seat 81 and stops the gasoline flow to the mixing chamber 48.

All danger of back-firing is prevented by the construction of my carbureter as described. The gases produced by the back fire, being in the mixing chamber 1 and necessarily above the piston valve, exert their full pressure upon the top 93 of the piston valve, coöperating with the action of gravity to close said valve instantaneously. As there is no drip of gasoline possible, no explosion or firing can take place in the carbureter or beneath it. My improved carbureter has several adjustable parts and therefore can be easily adapted to various conditions of the work required.

The quantity of primary air passing into the carbureter through the air inlets 58 and 59 in the bottom of the chamber 48 is controlled and regulated by the valve 67, which is set by hand to open or close the said air inlets wholly or partially to any extent desired, and when it is so set, it is held in its adjusted position by the engagement of the projection 71 with some one of the teeth 57 on the annular rim of the chamber 48. The quantity of air passing into the mixing chamber 1 through the auxiliary air inlet 30 is controlled and regulated by the auxiliary air valve 34, which opens or closes the aperture 30 to any desired extent, and is held in its adjusted position by means of the spring-pressed plug 39 in engagement with some tooth of the notched valve rim 35. The quantity of gasoline admitted to the chamber 48 is controlled and determined by means of the gasoline-feed regulator 73. The farther up the regulator 73 is screwed, the smaller is the discharge of the gasoline from the valve seat 81 when the needle valve 125 is raised by the piston valve.

As in my said Letters Patent No. 958,128, the piston valve, represented separately in Fig. 8, is both a throttle valve and an air valve. When the piston valve is in the posi-

tion illustrated in Fig. 5, the top 93 thereof and the upper cylindrical portion adjacent thereto completely throttle the discharge of the carbureted air from the mixing chamber 48; but when, under the suction-power exerted by the engine, the piston valve rises, the air outlets 88 thereof are open into the mixing chamber 1, and the carbureted air is delivered through the mixing chamber 1 and pipe 5 to the engine. To the same degree that the air outlets 88 are opened or closed, the air inlets 53 are opened or closed.

I claim as a novel and useful invention and desire to secure by Letters Patent:

1. In a carbureter, the combination of a tubular mixing chamber having side air-inlets; a discharge pipe from the mixing chamber to an engine; a tube mounted in the mixing chamber; an open-bottomed piston valve slidably mounted in said tube and movable therein by the suction of the engine, and having a circular top and a tubular body adapted to contact with said tube, and provided with mixture outlets through its sides adjacent to its top, said mixture outlets of the piston valve being closed by the outlet pipe of the mixing chamber when the piston valve is fully seated therein and said side air-inlets of the mixing chamber being closed by the tubular body of the piston valve when the piston valve is fully seated as aforesaid, but both said mixture outlets and air-inlets being open when the piston valve is partially raised in the tube of the mixing chamber; and a valve and valve aperture in the bottom of the mixing chamber for admitting primary air thereto.

2. In a carbureter, the combination of a tubular mixing chamber; a throttle valve slidably mounted in the chamber in contact therewith and having a tubular body; a downwardly extending, axially-directed valve stem carried by the throttle valve and having a valve head at its lower end with conically tapering sides; a nozzle having a bore; a detachable valve seat mounted in said bore at the upper end of the nozzle and provided with an upper central concavity into which said valve head is movable and also with a central longitudinal bore; a needle extending downward from said valve end, passing slidably through the bore of the valve seat and into the nozzle bore; means for supplying gasolene to the nozzle; and means for supplying atmospheric air to the mixing chamber.

3. In a carbureter, the combination of a tubular mixing chamber; a throttle valve slidably mounted in the chamber in contact therewith and having a tubular body; a needle valve carried by the throttle valve and provided with a head; a nozzle having a bore; a detachable valve seat mounted in said bore at the upper end of the nozzle and

provided with an upper central concavity into which the head of the needle valve is movable and also with a central longitudinal, tubular bore; a needle extending downward from said needle valve head, passing 70 slidably through the bore of the valve seat into the nozzle bore, which needle is formed with one longitudinal straight face and with the remainder of the longitudinal surface thereof conical; means for supplying gasolene to the nozzle; and means for supplying atmospheric air to the mixing chamber. 75

4. In a carbureter, the combination of a tubular mixing chamber having a bottom provided with air-inlets; a throttle valve 80 having a tubular body and slidably mounted in said chamber in contact therewith; a nozzle extending up through the bottom of the mixing chamber and provided at its upper end with a valve seat which has a 85 central longitudinal bore; an air valve having an aperture by which it is rotatably mounted on the nozzle beneath the bottom of the mixing chamber and adapted to cover or uncover said air-inlets; a needle valve 90 carried by the throttle valve and having a head adapted to fit in said valve seat; a needle extending from said valve head through the valve seat and the bore thereof into the nozzle bore; a nut engageable with 95 the nozzle to support said air valve in position; and means for supplying gasolene to the nozzle.

5. In a carbureter, the combination of a mixing chamber, a throttle valve slidably 100 mounted in the mixing chamber, a needle valve carried by the throttle valve and having a head, a nozzle having a longitudinal bore which is enlarged midway to form a gasolene chamber, a valve seat having a longitudinal bore and mounted detachably in the upper end of the nozzle bore, a gasolene feed regulator adjustably mounted and rotatable in the nozzle bore and having a longitudinal bore which extends downward and terminates in radial passages which open into said gasolene chamber, a gasolene supply pipe opening into said gasolene chamber, a bottom for the mixing chamber provided with air inlets, an oscillatory air valve 110 adapted to cover and uncover said air inlets, and a nut supporting said air valve and adjustably mounted on the nozzle. 115

6. In a carbureter, the combination of a mixing chamber having an opening through one side for the admission of auxiliary air; means for supplying primary air to the mixing chamber; means for supplying gasolene to the mixing chamber; a valve rotatably mounted on the mixing chamber and adapted to cover or uncover said opening at will, which valve has an arc-shaped edge provided with notches; and a plug adapted to hold said valve in position by engaging any one of said notches at will. 120 125 130

7. In a carbureter for operating an engine, the combination of a mixing chamber; a throttle valve normally seated in the mixing chamber; which throttle valve is movable upwardly by the suction of the engine and downwardly by gravity; a nozzle having a tubular bore and adapted to discharge gasolene beneath the throttle valve; means for supplying atmospheric air to the mixing chamber; means movable at will to vary the quantity of gasolene supplied to the nozzle and the quantity of atmospheric air supplied to the mixing chamber while the engine is in operation; a needle valve stem 10 mounted on the throttle valve and movable therewith; a gasolene-feed regulator longitudinally movable in the nozzle bore and provided with a longitudinal passage; a tapering needle valve carried by the needle valve stem and movable in said passage to control the discharge of gasolene therethrough; and means for supplying gasolene to said feed regulator in said passage thereof. 15
8. In a carbureter for operating an engine, the combination of a mixing chamber; a throttle valve normally seated in the mixing chamber; which throttle is movable upwardly by the suction of the engine and 20 downwardly by gravity; a nozzle having a tubular bore and adapted to discharge gasolene beneath the throttle valve; means for supplying atmospheric air to the mixing chamber; means movable at will to vary the quantity of gasolene supplied to the nozzle and the quantity of atmospheric air supplied to the mixing chamber while the engine is in operation; a needle valve stem 25 mounted on the throttle valve and movable therewith; a gasolene-feed regulator longitudinally movable in the nozzle bore and provided with a longitudinal passage; a tapering needle valve carried by the needle valve stem and movable in said passage to control the discharges of gasolene therethrough; and means for supplying gasolene to the feed regulator in said passage thereof. 30
9. In a carbureter, the combination of a mixing chamber; a piston valve slidably mounted in the mixing chamber; a shaft mounted in the mixing chamber and capable of an oscillatory movement therein; means for imparting oscillatory movement 35 to said shaft; a cam on said shaft adapted to contact with the upper end of the piston valve to impart to the piston valve a downward movement when the shaft is oscillated in one direction and to limit the upward movement of the piston valve when the shaft is oscillated in the opposite direction; a fixed nozzle having a bore and extending into the mixing chamber; a needle valve having a tapering needle and mounted 40 and movable with the piston valve; a gaso-
- lene-feed regulator movable in the nozzle bore and having a longitudinal passage, which regulator is movable along said needle; means for supplying gasolene to the feed regulator through said passage thereof; 70 and means for supplying atmospheric air to the mixing chamber. 75
10. In a carbureter, the combination of a mixing chamber, a combined throttle valve and air valve slidably mounted in the mixing chamber and having air inlets and mixture outlets, which inlets and outlets are open when said combined throttle valve and air valve rises by engine suction, but are closed when said combined throttle valve 80 and air valve is fully seated, a needle valve stem loosely mounted in said combined throttle valve and air valve and provided with a conical head, a tapering needle valve extending from said head, a fixed nozzle 85 having a longitudinal bore and also a valve seat at the upper end of said bore thereof adapted to receive the head of said needle valve stem, said needle valve extending slidably in a bore of the valve seat, and means 90 for supplying gasolene to said nozzle bore. 95
11. In a carbureter for an engine, the combination of a mixing chamber, having air inlets through its bottom and other air inlets through its sides, a throttle valve mounted in the mixing chamber and movable upwardly therein by the suction of the engine and downwardly therein by gravity, which valve has a closed top and side mixture outlets near its top, said mixture outlets 100 of the valve and said side air inlets of the mixing chamber being closed when the valve is fully seated, but which mixture outlets of the valve and said side air inlets of the mixing chamber are open when said valve 105 is raised by said suction, a nozzle in the mixing chamber whose discharging end is located opposite the lower edge of said side air inlets, a needle valve on the throttle valve adapted to open and close the nozzle 110 bore, and means for supplying gasolene to the nozzle. 115
12. In a carbureter for an engine, the combination of a mixing chamber, having an air inlet through its bottom, a tube provided with side air inlets, each of which last named air inlets is larger at its top than at its bottom, a throttle valve having a closed top and a tubular body which is slidably upwardly in the mixing chamber by the suction of the engine and downwardly by gravity, which side air inlets of said tube and which side inlets of the throttle valve are closed when the throttle valve is fully seated 120 in said tube, but are open when said throttle valve rises by said suction, a nozzle in the mixing chamber, whose discharging end is adjacent to the lower edge of each of the air inlets of said tube, a needle valve on the 125 throttle valve adapted to open and close the 130

nozzle bore, and means for supplying gasoline to the nozzle.

13. In a carbureter for an engine, the combination of a mixing chamber having conically flaring sides and also having a bottom with air inlets therethrough, means for regulating the quantity of air passing inwardly through the bottom air inlets of the mixing chamber, a tubular pipe mounted in the mixing chamber and having side air inlets, a throttle valve having a top which is normally in position flush with the top edge of said pipe and also having a body which is slidable in the pipe by the suction of the engine and provided with side mixture outlets near said top, which said air inlets of the pipe and said mixture outlets of the throttle valve are closed when the throttle valve is fully seated in said pipe but are open when the throttle valve rises by said suction, a nozzle mounted in the mixing chamber and having its discharging end adjacent to the side air inlets of said pipe, a needle valve on the throttle valve adapted to open and close the nozzle bore, and means for supplying gasoline to said nozzle.

14. In a carbureter for an engine, the combination of an outlet pipe from the mixing chamber to the engine; a mixing chamber having an air inlet in its bottom and also a tube from the mixing chamber provided with side air inlets; a throttle valve having a closed top and also a tubular body which is slidable in said tube by the suction of the engine, which side air inlets of the tube and side air outlets of the throttle valve are closed when the throttle valve is fully seated in the tube, but are open when the throttle valve is partially raised in said tube by the suction of the engine; a nozzle in the mixing chamber having a bore whose discharging end is located adjacent to the said air inlets of the tube; a needle valve carried by the throttle valve and adapted to open and close the nozzle bore; means of supplying gasoline to the nozzle; and means for regulating the current of air passing through the side air inlets of said tube and through said air outlets of the throttle valve.

15. In a carbureter for an engine, the combination of a mixing chamber having air inlets in its bottom, a tube from the mixing chamber provided with side air inlets; an outlet pipe from the mixing chamber to the engine, a throttle valve having a closed top and also a tubular body which is slidable in said tube by the suction of the engine, which side air inlets of the tube and said air outlets of the throttle valve are closed when the throttle valve is fully seated in the tube, but are open when the throttle valve is partially raised in said tube by the suction of the engine; a nozzle in the mixing chamber having a bore whose discharging end is located adjacent to said air inlets of the tube; a needle valve carried by the throttle valve and adapted to open and close the nozzle bore; means for supplying gasoline to the nozzle; and means for regulating the current of air passing through the bottom air inlets of the mixing chamber.

16. In a carbureter for an engine, the combination of a mixing chamber, an outlet pipe from the mixing chamber to the engine; a tube mounted in the mixing chamber; a throttle valve having a closed top and a tubular body slidable in said tube by the suction of the engine; a nozzle in the mixing chamber having a bore; a needle valve carried by the throttle valve and slidable in said bore; means for supplying gasoline to the nozzle; means for supplying atmospheric air in a vertical current into and through said mixing chamber into the tubular body of the throttle valve; and means for supplying atmospheric air in horizontal currents into said chamber substantially at right angles with said vertical air currents, which vertical and horizontal air currents in meeting each other at or near the discharging end of the nozzle are adapted to break up the gasoline jet from the nozzle into spray to make carbureted air.

In testimony whereof I affix my signature in presence of two witnesses.

ALBERT HOWARTH.
